UNITED STATES PATENT OFFICE.

HAYWOOD H. HILLYER, OF ST. LOUIS, MISSOURI.

DESIGN FOR A SERVICE BADGE OR BUTTON.

59,475.

Specification for Design.

Patented Oct. 25, 1921.

Application filed December 14, 1918. Serial No. 266,823. Term of patent 3½ years.

To all whom it may concern:

Be it known that I, HAYWOOD H. HILLYER, a citizen of the United States, residing at St. Louis, Missouri, have invented a new, original, and ornamental Design for a Service Badge or Button, of which the following is a specification, reference being made to the accompanying drawing, forming a part thereof.

In the accompanying drawing, Figure 1 is a front elevation of the service badge or button showing my new design.

Fig. 2 is an edge view thereof.

As shown my new design comprises a ring or circular band and a strip of relatively narrow width extending diametrically across the ring or band and having its ends in union therewith. On the ring or band above the center of the transverse strip the letter "A" is represented, and the letter "A" is also represented on the ring or band opposite each end of the strip. These three letters comprise the initial letters of the organiza-

tion known and styled as "American Army Association."

On the ring or band below the transverse strip are the characters "17—18," indicating the year 1917 in which year the United States entered the war against Germany, and the year in which Germany submitted to the terms of the nations at war against her.

The transverse strip is colored blue at one end and red at the opposite end, with a portion colored white between the blue and red end portions of the strip. These colors represent the colors in the flag of the United States.

As shown in Fig. 2, a fastener is in connection with the strip whereby the badge or button may be supported on the coat of the wearer.

I claim:

The ornamental design for a service badge or button as shown and described.

HAYWOOD H. HILLYER.
